UNITED STATES PATENT OFFICE.

WILLIAM FREDERICK HUNT, OF LONDON, ENGLAND.

DESIGN FOR A RECEPTACLE FOR ICE-CREAM.

SPECIFICATION forming part of Design No. 20,075, dated August 5, 1890.

Application filed April 16, 1890. Serial No. 348,233. Term of patent 3½ years. Registered in England January 24, 1890, No. 142,785.

To all whom it may concern:

Be it known that I, WILLIAM FREDERICK HUNT, a subject of the Queen of Great Britain and Ireland, residing at London, in the county of Middlesex, England, have invented and produced a new and original Design for a Receptacle for Ice-Cream, &c., (for which a patent has been granted to me in Great Britain, dated January 24, 1890, No. 142,785,) of which the following is a specification, reference being had to the accompanying drawings, forming part thereof, in which—

Figure 1 is a front elevation, Fig. 2 a plan, and Fig. 3 a vertical section, showing the design applied to a cup-holder.

The leading feature of this design relates to the ornamental appearance given to the

receptacle by the outer surface of the girdle, as shown, the same consisting of numerous ranges of corrugated or crumpled edges at *a* 20 projecting above the conical corrugated portion *e*. The receptacle *c* is represented as circular, and the contraction at *d* in the girdle is between the parts *a* and *e*, and a twisted handle is represented at *b*. 25

I claim—

The design for a receptacle for ice-cream, &c., substantially as described and shown.

WILLIAM FREDERICK HUNT.
